United States Patent Office.

IRA COPELAND, OF NORTH BRIDGEWATER, MASSACHUSETTS.

Letters Patent No. 73,300, dated January 14, 1868.

IMPROVED FRUIT-BOX.

The Schedule referred to in these Letters Patent and making part of the same.

TO ALL WHOM IT MAY CONCERN:

Be it known that I, IRA COPELAND, of North Bridgewater, in the county of Plymouth, and State of Massachusetts, have invented an Improved Fruit-Box; and I do hereby declare that the following, taken in connection with the drawings which accompany and form part of this specification, is a description of my invention sufficient to enable those skilled in the art to practise it.

This invention relates to the detail of construction of boxes to be employed for marketing small fruits, or for other purposes, in the matter of securing their covers, and also, in connection therewith, to provision for ventilating the contents of the boxes.

Figure 1 is an isometrical perspective of a box embodying my invention, with the cover in place to close the box.

Figure 2 is a similar view, but with the cover secured to the bottom of the box; and

Figure 3 is a cross vertical section of the box, with the cover secured to one side of the box.

One of the objects of my invention is the arrangement of the cover in such a way, and by such means, that whether the box is open or closed, its cover shall always be so connected with the box as to be secured from loss and protected by the box-body from breakage. This I accomplish by the employment of elastic cords, straps, or bands, which are attached either to the sides or ends of the box, about midway of their height, which elastics are also attached to the cover, or pass over it, or are attached to a strip or strips, which pass over the cover; and it is in such arrangement of elastics, in connection with the covers, and the sides or ends of a box, that this part of my invention consists, while the other parts of my invention depend upon combinations of devices, not novel in themselves, but new in combination with the said arrangement of elastics. The use of elastics on bill-files, pocket-books, &c., is well known to me, but in no instance am I aware of its employment in the manner herein described, that is to say, attached to sides or ends of a box about midway of the height thereof, so that they can turn like links or radii on or about the points of their attachment to said sides or ends, so that the box-cover can be held by the elastics to the top or bottom of the box, with about an equal strain on the elastics in either case.

In all the drawings, *a* represents the sides of my box, *b* the ends, *c* the bottom, *d* the top, and *e* the elastics, usually and preferably pieces of rubber, or rubber cord or braid, or they might be made as or of helical springs.

The Figures 4 and 5 show modifications of the manner of applying the elastics *e*, each modification retaining, however, the distinctive characteristic of my invention in the matter of its attachment to the sides or ends of the box, at about the middle of their height. In all the figures the points of attachment of the elastics to the box-body are marked *f*, and are about in the centre of the height of boxes shown, while they vary as to the detail by which they are made to operate upon the cover. In figs. 1, 2, and 3, cleats are fixed on the top surface of the cover, and the knotted ends of the elastics are caught into suitable recesses formed in the cleats and cover. This arrangement I deem preferable for what I term half boxes, as thereby the part of the elastic is saved which in fig. 5 is shown as passing over the outside of the cover, said part having but little elastic operation. In the whole or square box shown in fig. 4, I make use of slats *h*, to which the elastics are confined, as they are in the cleats *g*. To prevent the cover from slipping sideways or endways on the top of the box, I place steady-pins, *i*, in the tops of the ends, and make corresponding depressions in the underneath side of the cover. To provide for ventilation, I make the bottom narrower than the width of the box, and if desired pierce it with holes. At the top I make the sides fall short of the entire height of the ends. These half boxes I make of such proportions that they pack conveniently in nests of four when empty, the ends of two being inserted into the other two, and crosswise with respect to the same. Between the cleats *g*, and on the top of the cover *d*, the necessary labels may be located, they being protected from injury by the cleats, whether the cover is on the top of the box closing it, or whether it is beneath the box, or on its side, as when empty or disclosing its contents. When these boxes are full, and are packed in crates, the cleats keep the adjacent tops and bottoms sufficiently apart to let the air circulate and enter the boxes through the openings left by the narrow bottom.

The construction described supplies a want long felt of a cheap box for marketing fruit, in which sufficient

ventilation can be had, which will pack closely both full and empty, and in which the cover is not liable to be lost or injured.

I claim a box, in which the cover is secured to the body by means of one or more elastic media, arranged so as to operate substantially as described.

Also, providing a cover, when secured as described, with cross-pieces on its outer surface, so that said cross-pieces serve to keep apart the bottoms and tops of adjacent boxes when packed in crates, and thus permit circulation of air between the boxes, and also serve as feet for the boxes to rest upon when the cover is secured beneath the box, as in filling, or when used as a show-box, and prevent injury to any marks or labels which are upon the outer surface of the cover.

Also, in combination with a box in which the cover is secured as described, and with such cover, the dowel or steady-pins and holes, substantially as and for the purpose specified.

Also, in combination with elastic media, secured to the sides or ends of boxes substantially as described, cross-bars, or slats, or strips of wood, or other suitable material, which serve to reduce the length and cost of the elastics.

IRA COPELAND.
